HAIR ROLLER TRAY

Kenneth Reiner, Box 54091, Terminal Annex,
Los Angeles 54, Calif.

Filed Apr. 10, 1964, Ser. No. 79,435

Term of patent 14 years

(Cl. D58—13)

FIG. 2.

FIG. 3.

FIG. 4.

FIG. 5.

I claim:

The ornamental design for a hair roller tray, as shown.
